UNITED STATES PATENT OFFICE.

JAMES A. GORMAN, OF SPOKANE, WASHINGTON.

GAME.

Application filed July 21, 1924. Serial No. 727,283.

To all whom it may concern:

Be it known that I, JAMES A. GORMAN, a citizen of the United States, residing at Spokane, in Spokane County, and State of Washington, have invented certain new and useful Improvements in Games, of which the following is a specification.

The present invention relates to improvements in games based upon the game of baseball, and in which is employed chance game-pieces or dice in connection with a game board. In carrying out my invention I preferably utilize eleven dice, the sides of which are of various distinguishing colors and bear different symbols, and in addition one of the dice is of special shape, whereby the plays are indicated in the game. Two opposing teams are employed which teams may consist of as many players as desired within limits, and these teams alternate at the bat and in the field according to the well established rules of the national game, thus insuring an interesting, attractive, and novel means of entertainment.

In the accompanying drawings I have illustrated one complete set of the devices for carrying out my invention, these devices being combined and arranged according to the best mode I have thus far devised for the practical application of the principles of my invention.

For convenience of illustration and description I have shown the cubes or dice in flattened or diagrammatic form in order that the indicated plays may be compactly exhibited.

Figure 1 is a view of a special form of device known as a cocked dice having two flattened corners and provided with the symbols ball, strike, hit &c. said dice being used by the player termed a pitcher.

Figure 2 is a flattened cube bearing the symbols for indicating a fair or foul ball.

Figure 3 represents a dice showing the nature of a hit ball, whether a fly or ground ball.

Figure 4 represents a dice having thereon symbols to indicate the position, infield or outfield to which the ball is hit.

Figure 5 designates the nature of the play, whether safe or out.

Figure 6 is a dice used with Figure 5 to show an error.

Figure 7 is a dice used to indicate an additional base on the hit.

Figure 8 is a single dice used electively for stealing bases.

Figures 9, 10, and 11 are separate dice representing respectively one, two and three men or runners occupying bases.

Figure 12 is a perspective view of the game board used in the game.

For convenience in identifying the individual dice they will be referred to and designated by the numerals corresponding to the figures of drawings, as 1 through 11, and the game board is designated 12. The board is in the shape of a diamond and is provided with indicators 13, 14 and 15 for counting strikes, balls, and the number out, respectively. A score board 16 is indicated on the game board for scoring runs by innings, and a counter 17 is provided for keeping the scores of the opposing teams by half-innings, i. e. the score of the team at bat.

The sides of the several dice are provided with various colors and these different colors are used as an aid in quickly determining the play indicated. The colors are designated in the drawings according to the chart of the Patent Office. The colors yellow and blue in Figure 1, or on dice 1, indicate a strike and ball respectively, and do not occur on any other cube. The color brown is used on dice 2 only and this color is employed in connection with the word foul for quickly ascertaining the nature of a hit ball. White or the absence of color is used on all of the dice to designate a fair or safe play, while red occurring on dice 5, 8, 9, 10 and 11, indicates an out in all cases.

All plays are indicated by the symbol and color appearing on the uppermost side of the dice when the latter is thrown or tossed on the game board 12.

To determine the order of play by teams, the dice 8 is thrown, this dice having an even number of red and white faces respectively, to insure an even chance to the contestants. A representative of one team calls his color, and a representative of the other team throws the dice. The winner of the choice according to the color appearing uppermost on the dice is entitled to choose for his team its appearance at the bat—that is first or last innings.

Before play is started the several dice are distributed, the team at bat receiving dice 2, 3, 4, 7 and 8, and the team in the field receiving the remaining dice 1, 5, 6, 9, 10, 11,

and these dice are thrown, or tossed in usual manner on the game board 12, for the purpose of indicating plays according to the established rules of the game of baseball.

- 5 The object of the game of course is to get runners on the bases, advance the runners around the bases and have them pass the home plate for scores. The home plate is indicated in Figure 12 by the numeral 18, and
 10 first, second and third bases or bags are designated respectively as 19, 20, 21, while the pitcher's box is indicated as 22.

Disks, buttons, or other devices (not shown) may be used to represent the batter 15 and base runners, and these men are placed in the box at the plate and on the bases as runners and advanced or removed according to the regular rules of the game and the 20 plays indicated by the thrown device or dice.

The team in the field starts play with the single dice 1 and a player of this team called the pitcher first throws or tosses the 25 single dice for the batter and for successive batters until three players are out, after which the sides are changed as in usual base ball.

The throw of the single dice 1 by the 30 pitcher has the possibility of four resulting plays—a ball, a strike, a hit ball, or a batter hit by the pitched ball, the last mentioned play being indicated if the cocked dice stands upon one of its flattened corners. The other plays are indicated by the words 35 ball, strike, and hit.

Should the dice roll or depart from the 40 board the throw will indicate a wild pitch, usually scored as a ball. By any three succeeding throws of the dice 1 the batter is retired on strikes as indicated when the strike face of the dice is up. By four succeeding throws of the dice with the ball face up the batter is given his base on balls and a disk or button, the first runner, is placed 45 on first-base 19.

In the event that the single dice 1 as thrown comes with the word hit on its upper face, the batter does not immediately take 50 first base—the nature and extent of the hit is first determined by throwing additional dice, by the team at bat. A player of this team now throws a bunch of dice 2, 3, 4, and 7 which respectively will determine 55 whether the hit ball went into foul or fair territory; whether it is a fly or a ground ball; the infield or outfield position to which the ball was hit; and if fair, the number of bases to which the batter is entitled i. e. whether it is a single, a double or a triple 60 or home run. These four latter hits are provided for by the black squares appearing on the white surfaces or sides of the cubes in Figs. 2, 3, 4, and 7.

65 For example if the pitcher throws dice 1 with one of its white sides uppermost the

play is a hit ball. Then when the four dice 2, 3, 4, and 7 are thrown, if their white sides are uppermost the indication is that the ball was hit into fair territory. If the brown side of dice 2 shows uppermost a 70 foul is indicated, which then becomes an additional strike on the batter, and its value is determined by the regular rules of the game.

Assuming however that the ball has been 75 hit into safe territory, as indicated by dice 2; dice 3 indicates whether it is a fly or a ground ball; dice 4 indicates the field or position to which the ball was batted, and the black squares appearing on the four 80 dice indicate the number of bases from one to a home run, to which the batter is entitled. Should the black squares be entirely absent the batter has made a scratch hit. If a runner or runners are on the bases the batter 85 is credited with a sacrifice hit and the runners are advanced one base, provided two runners are not already out.

Following the play of the game, the team 90 in the field now is entitled to toss its two dice 5 and 6 with the chance of retiring the runner as indicated by the four out sides of dice 5 and the eight safe sides of dice 5 and 6. When these two dice are thrown if 95 a white side reading safe come uppermost on dice 5 the player is safe regardless of the indications on dice 6.

Should the word out on any one of the 100 four red sides of dice 5 appear uppermost, the batter is out. Should the letter E appear on both the dice 5 and 6, the team throwing the dice 5 and 6 is credited with 105 an error and the batter is safe, and the batter and base runner (or runners) advance the number of bases indicated by the black squares appearing uppermost on the dice 2, 3, 4, and 7.

The dice 9 10 and 11 are used selectively by the team throwing the dice 5 and 6. That is a combination of 5 6 and 9 is thrown 110 when one runner occupies the bases; 5 6 9 and 10 are thrown with two men on the bases; and 5 6 9 10 11 are thrown when three men occupy the bases. Dice 5 and 6 determine the status of the batter and the 115 respective dice 9 10 and 11 determine the status of the runner or runners. After two men have been put out the dice 9 10 and 11 are withdrawn from play regardless of 120 whether or not the bases are occupied. The numerals on the respective dice 9 10 and 11 indicated the respective bases occupied by the runners, as first, second and third.

Assuming that the bases are loaded and 125 none out and that the batter has made a hit as determined by the dice 1 2 3 4 and 7, the team in the field throws the five dice 5 6 9 10 11. If all five dice are white side up all runners are safe and they advance over 130 the bases as indicated by the squares on

dice 2, 3, 4, 7. If one red side appears uppermost in group 5 6 9 10 11 one player is out. This player is determined to be the batter indicated by B on dice 5, the first 5 runner indicated by dice 9, the 2nd runner indicated by dice 10 or the third runner indicated by dice 11. Of course others will be out if so indicated by the several dice.

The dice 8 is used electively by the side 10 at bat and is thrown singly by the runner or player on the base, and only when a runner is on base. The chances are even on stealing the base as indicated by three white sides for steals and three red sides for out 15 stealing on the dice 8. If white appears on the thrown dice the runner is advanced one bag; if red appears the runner is out and the score is kept accordingly.

The game is continued as above indicated 20 until three men or the in side have been retired for the first half of an inning, then the team in the field becomes the team at bat and vice versa, for nine innings, or for a predetermined number of innings, as de- 25 sired.

Various exceptions and rules, consistent with the regular base ball rules, may be incorporated, as for instance assuming that a runner is on first, or runners are occupying 30 first and second, or all the bases loaded. The batter hits a grounder into fair territory on which he is retired at first as the runner or runners advance, such play on the part of the batter will be scored as a sacrifice hit. 35 Again, with a runner on third and one out, if the batter is retired on a three base fly, the runner on third is advanced one base and scores a run.

Of course the team making the most runs 40 in a predetermined number of innings wins the game, and the pitching of the ball, i. e. throwing of dice 1 is carried out after each successive play.

The dice in the series used are divisible 45 into sets, one for the in side or the side at bat and one for the out side or side in the field. These sets are for use in groups by the respective sides; a single die representing the pitcher is used by the out side or the 50 side in the field; a single dice is electively

used by the team at bat for base stealing; and group for base runners is selectively used by the in side or team at bat.

Having thus fully described my invention, what I claim as new and desire to secure by 55 Letters Patent is—

1. In a baseball game a series of dice comprising two sets representing the team at bat and the team in the field and bearing symbols indicating plays, one dice of the team 60 at bat being adapted for selective use, one dice of the team in the field being adapted for pitcher's use, and the remaining dice being adapted for group use.

2. In a base ball game a series of dice comprising an at-bat set and an in-the-field set, one dice in the latter set bearing symbols for plays on pitched balls and adapted for single use, a single dice in the former set bearing symbols for base stealing and also adapted 70 for single use, and the remaining dice of said sets bearing symbols for group use.

3. In a base ball game a series of dice comprising two sets representing the team at bat and the team in the field and bearing symbols indicating plays, said dice having contrasting colors as auxiliary identifying means in connection with said symbols, one dice of the team at bat being for selective use and one dice of the team in the field being 80 adapted for pitcher's use.

4. In a base ball game the series of dice comprising an at-bat set and an in-the-field set bearing play symbols and adapted for group use, one of said dice in the second set 85 being adapted for single use by a pitcher and provided with a flattened corner for indicating a play when said dice stands on said corner.

5. In a base ball game the series of dice 90 comprising an at-bat set and an in-the-field set bearing play symbols, one of said dice in the first set being adaptive for elective use for base stealing, one of said dice in the second set being adapted for single use by a 95 pitcher, and a group of dice for base running plays in the first set adapted for selective use in said set.

In testimony whereof I affix my signature.

JAMES A. GORMAN.
